DESIGN FOR A COMBINED SERVICE TRAY AND CONTAINERS FOR HAIR AND SCALP TREATMENT OR THE LIKE

Robert M. Brooks, Long Island City, N. Y., assignor to Antiseptol Company, Inc., Chicago,
Ill., a corporation of Illinois

Application July 1, 1940, Serial No. 93,376

Term of patent 7 years

To all whom it may concern:

Be it known that I, Robert M. Brooks, a citizen of the United States, residing at Malba, Long Island City, in the county of Queens and State of New York, have invented a new, original, and ornamental Design for a Combined Service Tray and Containers for Hair and Scalp Treatment or the like, of which the following is a specification, reference being had to the accompanying drawing, forming part thereof.

Figure 1 is a perspective view of a combined service tray and containers for hair and scalp treatment or the like, embodying my new design.

I claim:

The ornamental design for a combined service tray and containers for hair and scalp treatment or the like, substantially as shown.

ROBERT M. BROOKS.
